United States Patent Office.

BENJAMIN SCHOPF AND CHRISTIAN SCHOPF, OF PITTSBURG, INDIANA.

Letters Patent No. 99,244, dated January 25, 1870.

IMPROVEMENT IN LIFTING-JACKS.

The Schedule referred to in these Letters Patent and making part of the same

To all whom it may concern:

Be it known that we, BENJAMIN SCHOPF and CHRISTIAN SCHOPF, of Pittsburg, in the county of Carroll, and State of Indiana, have invented a new and useful Improvement in Lifting-Jacks; and do hereby declare the following description, taken in connection with the accompanying plate of drawings, hereinafter referred to forms a full and exact specification of the same, wherein we have set forth the nature and principles of our said improvement, by which our invention may be distinguished from others of a similar class, together with such parts as we claim and desire to secure by Letters Patent.

Our invention relates to that class of mechanical devices termed lifting-jacks, and consists of a fulcrum-standard, lifting-beam, and operating-lever, connected together by metallic straps or links, in such a manner as to produce a mechanism of great power, when in operation, and which may be folded up compactly when not in use.

In the accompanying plate of drawings, which illustrate our invention, and form a part of the specification thereof, and in which corresponding parts are indicated by similar letters—

Figure 1 is a view of the jack, set ready for lifting, and

Figure 2 represents the said jack folded together.

The construction and operation of our invention are as follows, to wit:

A represents the lifting-beam, provided with the cheeks *a a* for the load to be raised to rest on, and the shoulder *a'* to receive the end of the operating-lever.

B is the fulcrum-standard, rounded at its upper end to fit within the shoulder *c*.

C is the operating-lever, provided with a shoulder, *c'*, indicated in the figure by dotted lines.

The said operating-lever and fulcrum-standard are

connected together, by means of the obtuse-angled cheeks E and bolts *e*, in such a manner that the said fulcrum-standard is free to describe an arc about the bolt by means of which it is secured to the said obtuse-angled cheeks.

The said lever and lifting-beam are connected together by means of the cheeks or links F, and the bolts *f*, in such a manner that they, to wit, the said lever and lifting-beam, may be revolved about the said bolts as centres.

When in operation, the jack is placed in position, as shown in fig. 1, with the shoulder *a* under the object to be raised. The rounded end of the lever C is then inserted beneath the shoulder *a'*, and force applied thereto.

The fulcrum-standard B forms a firm support for the said lever, the end thereof working within the shoulder *c* of the same.

When it is desirable to pack or fold the jack for the purpose of transportation, or other reason, it is only necessary to revolve the operating-lever C toward the lifting-beam A. The end of the said lever then passes clear of the shoulder *a'*, and the parts of the machine assume the position indicated by fig. 2.

Having described the nature, construction, and operation of our invention, we will designate what we claim as new, and desire to secure by Letters Patent, in the following clause:

The lifting-beam A, fulcrum-standard B, operating-lever C, cheek F, and angular cheek E, when arranged to operate as described.

BENJAMIN SCHOPF.
CHRISTIAN SCHOPF.
